HANGER FOR DRAPERYES

Filed Nov. 1, 1934

UNITED STATES PATENT OFFICE

2,051,342

HANGER FOR DRAPERYES

Charles S. Nudelman and Harry Kruglick,
Chicago, Ill.

Application November 1, 1934, Serial No. 751,056

9 Claims. (Cl. 156—20)

Our invention, in its broad aspect, has to do with improvements over the type of invention shown in our prior Patents #1,819,379 granted August 18, 1931, and 1,945,228 granted January 30, 1934; and more particularly it is our purpose to provide, among other things, the following additional and unique features and advantages in this general class of invention;—

First; to provide an improved curtain rod which may be curved or straight; cut to length or formed in telescopic sections, and which is relatively light, strong and provides at the same time for free movement of hanger fittings thereon; and which may be so formed as to serve for mounting heavy stage curtains; Second; it is our purpose to provide unique and improved fittings for mounting the rod on a base, and wherein certain adjustability is provided and a minimum number of screws and the like, and wherein there are provided pulley mountings so formed and set that the draw cords will not bind and will have free play, and which are reversible. Furthermore our pulleys are set in the normal line of the cords so that traversing is not hindered, and at the same time the least number of parts, screws and rivets are used; Third, we especially emphasize the unique and advantageous construction of our so-called combination slides as defined in the present application, and wherein the slides proper serve in the nature of improved keepers for E-shaped locking fittings for taking the loops of draperies wherein these slides catch the loops so that the draperies are hung in pleats in the most desirable manner; furthermore, our slides and locking fittings are adapted to receive and mount reversible lapping masters, so that by a very simple two part fitting we are enabled to accomplish a number of desirable results. Our slides furthermore are designed to take pin fittings for draperies, and the manner of attaching the cords thereto is improved, while the entire construction is rendered less liable to become out of order and more easily manufactured and set up; Fourth; we provide a unique lapping master, the construction of which is greatly simplified and which, in cooperation with the slides and E-fittings provides a simple and advantageous mounting; Fifth; we provide a new and desirable bracket which is in the form of a casting and which has means for catching the last loop of a drapery, and which does away with threading, and has three curtain adjustments so that where top and bottom hung curtains are used the same may be adjusted for shrinkage; furthermore the bracket is fully reversible; Sixth; in our pulley arrangement, the

pulleys are set so that the cords will traverse freely and to that end the same are set to the shape of the rod with the respective pulley wheels staggered; and Seventh; we greatly simplify the construction and fittings used in our prior patents as well as others in the art, and we here provide a unique and advantageous drapery assembly including the several fittings therefor, which will permit free adjustment and hanging of draperies and free movement of the same on either a curved or straight track, and it is to be understood that the various parts of our invention are subject to changes as to size, shape, form and position and other details of construction, provided such changes fall within the scope of our inventive concept and the purview of our claims.

In the drawing, wherein we have illustrated the preferred form of our invention;—

Figure 1 is an assembly view showing the arrangement of rods, brackets, pulleys, slides and cords, in conjunction with a known type of drapery;

Figure 2 is a top plan view showing particularly the manner of looping or tying the cord to the slides;

Figure 3 is a perspective detail view of one of our fittings;

Figure 4 is an end view thereof;

Figure 5 is an enlarged detail of one of our E-shaped locking fittings showing the manner of setting the loops of a curtain thereon to hang the same in a pleat;

Figure 6 is an enlarged detail of one of our slides with the E-shaped locking fitting shown in place by dotted lines;

Figure 7 is an assembly view of one of our lapping masters and an E-shaped locking fitting;

Figure 8 is an edge view of the construction shown in Figure 7; wing arrangement for locking barrel shown in Figure 12 into bracket as shown in Figure 15;

Figure 9 is an end view of one of our pulley assemblies;

Figure 10 is a modified form thereof;

Figure 11 is another view of one of our pulley assemblies;

Figure 12 is a cross section of the collar or barrel for attaching the pulley assemblies to the bracket;

Figure 13 is an end view of the part shown in Figure 12;

Figure 14 is a form of our slide without lugs or track fittings and designed for use with blinds or curtains; view A is an end view and, view B a side view, and

Figure 15 is a detail view of one of our improved brackets showing means for catching the end loop of a curtain and at least three vertical adjustments.

Figure 16 is a sectional view of a modified form of our curtain rod.

In the drawing wherein like characters are used to designate like or similar parts throughout the several views:—

10 The numeral 1 designates a curtain or drapery, and which has a top braid 2 and a series of loops 3. These parts are not included within our invention and are shown merely for illustration of its application.

15 We provide either a solid or a tubular track member 4 which has upper and lower grooves (and which will hereinafter be called the curtain rod); this track may be cut to length or telescopic and either curved or straight; and as shown in Figure 16 it may be open on one side with the track formed adjacent the edges 4a. Designed to engage the ends of the curtain rod 4 are cylindrical fittings 5 or barrels; the rod being clamped in place by screws 6; fittings 5 have square ends 9 which fit in bracket 7; these cylindrical fittings 5 are attached to the brackets 7 by a wing screw 8. The brackets (as shown in Figure 15) may be provided with cut away parts forming a finger, top and bottom, designated by the numeral 10 to catch the last loop of a curtain, and a series of three adjustments 11 for top and bottom mounted curtains to provide for shrinkage; the brackets are one piece castings and are reversible and very simple in construction.

35 Fitting next to the ends of the cylindrical fittings 5 are pulley mountings 12 held in place by screws 13; it will be noted that the several pulleys 13—13a and 13b are set substantially about the circumference of the rod, or staggered, so that they are in line with the traversing cords 14; the center pulley 13 is the largest and is positioned to give free play to the cord; the smaller pulleys serve either to take the return 40 of the cord or serve as idler pulleys to insure easy operation. A modified form of our pulley assembly is shown in Figure 10, wherein the form and shape of the body is slightly modified thus combining the barrel of the bracket and pulley together. Ordinarily the cord 14 is trained over the pulleys and along the length of the curtain rod as shown in Figure 1.

50 Arranged at intervals on the curtain rod are a series of unique slides 15 which are one piece and have upwardly and downwardly bent portions or flanges 16 fitting in the upper and lower grooves of the curtain rod 4 to mount the slides thereon, and other portions or flanges 17 on the front of the slide bent forward and toward each other in spaced relationship in a vertical place to form keepers or tracks for the E-shaped locking fitting 18 shown in detail in Figures 5 and 6. The slides 15 have upper and lower lugs or eyes 19 to receive pin type fittings 55 for draperies, and to serve after the manner shown in Figures 1 and 2 to catch the cord 14 by looping the same over a lug 19 thereby to catch the slide on the cord so that the curtain mounted on the slide can be moved and adjusted by drawing the cord. Thus in brief terms each slide is a one piece affair having opposed rear and horizontally arranged flanges or parts 16; and opposed front and vertically arranged flanges or parts 17 with upper and lower eyes 70 or lugs 19.

5 The E-shaped locking fittings 18 have a vertical bar 20 and a series of three spaced horizontally arranged bars 21; the uppermost of which has end ears 22 and all of which have inwardly bent ends 23 to space the fitting from the inner face of the slide when it is inserted as shown in Figure 6. The exact form, size and shape of the locking fittings may be subject to some variation without departing from the spirit of the invention. In practice the loops 3—preferably adjacent pairs—are caught over the top bars 21 of the E-fittings, with one part over the middle bar, and both parts back of the bottom bar, so that when the E-fitting is slid between the portions or tracks 17 of the slides 15 the loops will be locked in place as shown in Figures 1 and 5; it being understood from the construction that ears 22 prevent the E-fittings from slipping straight through the slides.

10 Our reversible lapping master is shown in Figures 7 and 8, and is a modification of one of our slides 15 since the head end of a master designated by 24 is formed like a slide and has an integral arm 25 with a rearwardly bent end part 26 terminating in a T-foot 27 provided with a raised center part 28 to receive thereunder the middle bar of an E-fitting while the ends of the T-foot are caught beneath the top and bottom bars of an E-fitting as shown in Figures 7 and 8 thereby to support the lapping master 15 from the ordinary slides and E-fittings as shown.

15 In operation; the brackets 1 are suitably mounted by screws or the like, and the curtain rod fixed thereon by cylindrical fittings 5; the pulley mountings are then fixed in place and the rod assembly is rigid. The slides 15 are then properly arranged and the cord 14 caught over the lugs 19 whereupon the E-shaped locking fittings are adjusted through pairs of adjacent loops as shown in Figure 5 to form the pleats and these are in turn slipped into the slides as shown in Figures 1 and 6 to mount the curtain; the lapping parts of the curtain being supported by the lapping masters shown in Figures 7 and 8. In Figure 14, views A and B, is shown a simplified type of slide with a screw mounting 29 for shades and blinds.

20 As heretofore pointed out, certain changes may be made in form, shape and size without departing from the spirit and scope of our invention, and for that reason it is again emphasized that the detailed construction of the same as outlined in the foregoing may be changed provided such changes fall within the scope and purview of what is claimed.

25 We claim:—

1. A hanger for draperies, comprising a slide having opposed horizontal members for engaging a support, and opposed vertical members, and substantially E-shaped locking fitting slidable 30 devices received between the opposed vertical members of said slide and removable therefrom for engaging a drapery to hang the same from the slide.

2. A hanger for draperies comprising a one-piece slide for a curtain rod; said slide formed with rearwardly, opposed, spaced horizontally arranged members engaging the rod; and opposed, spaced, vertically arranged members integrally formed on the front of the slide; a substantially 35 E-shaped locking member formed with opposed spaced ears on its top part for removable engagement in the front vertical members of the slide; said slide having upper and lower lugs for attaching pin curtains, and the bars of the E-shaped 40

member adapted to engage the loops of a loop suspended type of curtain.

3. A combination attachment for hangers for draperies, comprising a slide formed with a body and opposed, spaced, rearwardly bent members for engaging a track to mount the slide; said slide having opposed, spaced, vertically bent members in front; and a fitting receivable in the front members and removable therefrom to attach a 10 drapery thereto.

4. A combination attachment for hangers for draperies, comprising a slide formed with a body, and opposed, spaced, horizontally arranged rearwardly bent members for engaging a track to mount the slide, said slide having opposed, spaced vertically arranged forwardly bent members; an E-shaped fitting receivable in the forwardly bent parts and having ears to catch the same thereon; said fitting being removable and designed to receive a drapery thereon to hang the same with 20 pleats.

5. A combination attachment for hangers for draperies, comprising a slide formed with a body, and opposed, spaced, horizontally arranged rearwardly bent members for engaging a track to mount the slide; said slide having opposed, spaced, vertically arranged forwardly bent members, a fitting removable in the vertically arranged members, and a lapping master having a head end, and a T-shaped foot end, the T-shaped end being lockable in the fitting when it is engaged therewith and locked on the slide with the fitting when the fitting is engaged in the 30 slide.

6. A combination attachment for hangers for draperies, comprising a lapping master formed with a head having vertically spaced apart for-

wardly bent members; a slide for engagement on a supporting rod, and a locking fitting having spaced, horizontal members; the slide being formed with vertically spaced apart forwardly bent members; the locking fitting designed to be 5 received in either the spaced vertical members of the slide or the head end of the lapping master; said lapping master having a foot end, and the foot end having outstanding part designed to be received between the horizontal bars of a fitting 10 carried by the slide to mount the master on the slide, and the fitting serving a dual purpose of a removable mounting for a drapery carried on the slides and the master lapping member.

7. A one piece sheet metal attachment for 15 drapery hangers comprising a body portion, lugs having eyes formed therein at the top and bottom of the body portion, and rearwardly bent, spaced, horizontally arranged members on the body, and forwardly bent, spaced, vertical members 20 on the body.

8. A one piece sheet metal attachment for draperies of the type suspended by loops comprising an attaching fitting for the draperies including spaced horizontal bars and a vertical bar 25 joining the horizontal bars; ears on the uppermost horizontal bar, and the horizontal bars designed to receive adjacent loops of the drapery to hang the same with pleats.

9. A lapping master for drapery hangers, comprising a head end formed with spaced, forwardly bent and vertically arranged members, an integral outstanding arm, and a T-shaped foot on the arm designed to engage a part of a hanger assembly. 30 35
